J. ANDREW

BOTTLE

Filed Sept. 4, 1924

James Andrew
Inventor
(His mark).

UNITED STATES PATENT OFFICE.

JAMES ANDREW, OF WASHINGTON, DISTRICT OF COLUMBIA.

DESIGN FOR A BOTTLE.

Application filed September 4, 1924. Serial No. 10,672. Term of patent 14 years.

To all whom it may concern:

Be it known that I, JAMES ANDREW, a citizen of Greece, residing at 601 Louisiana Avenue NW., Washington, D. C., have invented a new, original, and ornamental Design for Bottles, of which the following is a specification, reference being had to the accompanying drawing, forming part thereof.

The figure is a front elevation.

I claim:

The ornamental design for a bottle, as shown.

JAMES ^{his} ANDREW.
